UNITED STATES PATENT OFFICE

100,104

DESIGN FOR A COAT

Morris Hiller, Long Beach, N. Y.

Application May 22, 1936, Serial No. 62,770

Term of patent 3½ years

To all whom it may concern:

Be it known that I, Morris Hiller, a citizen of the United States, residing at Long Beach, Nassau County, New York, have invented a new, original, and ornamental Design for a Coat, of which the following is a specification, reference being had to the accompanying drawing, forming part thereof.

Fig. 1 is a perspective view of applicant's coat illustrating the collar design in closed position;

Fig. 2 is a perspective view showing the symmetrical appearance of the collar in open position;

Fig. 3 is a fragmentary rear view of the coat disclosed in Fig. 1, slightly in perspective showing the collar design;

Fig. 4 is a fragmentary view of the sleeve, slightly in perspective, showing the sleeve design.

I claim:

The ornamental design for a coat substantially as shown and described.

In testimony whereof, I affix my signature in the presence of two witnesses.

MORRIS HILLER.
